UNITED STATES PATENT OFFICE.

CLINTON F. SHADLE, OF INDIANAPOLIS, INDIANA, ASSIGNOR TO INDIANA EQUIPMENT CORPORATION, OF INDIANAPOLIS, INDIANA, A CORPORATION.

TRAIN-CONTROL-VALVE CONSTRUCTION.

Application filed January 11, 1924. Serial No. 685,559.

To all whom it may concern:

Be it known that I, CLINTON F. SHADLE, a citizen of the United States, and a resident of Indianapolis, county of Marion, and 5 State of Indiana, have invented a certain new and useful Train-Control-Valve Construction; and I do hereby declare that the following is a full, clear, and exact description thereof, reference being had to the accompanying drawings in which like numerals refer to like parts.

This invention relates to a train control system, and particularly to a valve construction included in said system. This invention also is an improvement upon and an 15 extension of a valve construction illustrated and described in the co-pending application, Serial No. 621,262, filed February 26, 1923.

20 The chief object of the invention is to provide a valve construction of the general character hereinbefore indicated which is adapted to function in a complete train control system, or be otherwise applied as 25 found desirable.

The chief feature of the invention consists in providing for a fluid pressure conduit, an exhaust construction controlled by a valve, which valve is electro-pneumatically controlled, and which exhaust is of 30 a determinable character. Said exhaust is adapted to be manually controlled and is also adapted to be automatically controlled by electro-pneumatic means. Said electro-pneumatic controls are connected in parallel 35 both electrically and pneumatically and are so arranged structurally that one of the controls is only operable when the other control is operated.

40 Another and important feature of the invention consists in providing an additional fluid pressure conduit, which also exhausts through the beforementioned exhaust construction and which is also controlled by the first-mentioned exhaust controlling valve.

Still a further feature of the present invention consists in a normally open fluid pressure conduit which is simultaneously 45 closed by the first-mentioned valve when both of the fluid pressure conduits previously described are associated with the exhaust. The necessity for this particular construction is that in the present railway equipment upon heavy locomotives, it is im-

possible for the engineer or engineman to know whether or not the driver brakes are creeping until such creepage is sufficient to exert pressure by the brake shoes upon the tires, causing a heating of the latter and 60 finally the throwing of the same. Brake creepage of the engine brakes including drivers is caused by a drop in train pipe pressure in the train line. On long freight trains, as well as passenger trains where the 65 pressure is relatively high, the supply pump is unable to maintain the train pipe pressure against train pipe leakage. Such leakage or drop in pressure causes the distributing valve piston to move from its normal 70 position sufficiently which permits air to leak through to the graduating valve, moving the same sufficiently to permit air to leak through to the engine brake cylinders, 75 thus causing said creepage. In the present 75 type of heavy locomotives, a U-pipe connection has been applied as a by-pass connecting the distributing valve to the release brake, which eliminates the foregoing 80 creepage. The addition of an automatic 80 control to a locomotive so equipped will not function perfectly unless the train control valve construction herein described controls this U-pipe connection or by-pass as well.

Still a further feature of the invention 85 which is capable of a broader application than the foregoing is the control of a restricted communication from the exhaust conduit to the exhaust, which secures a retardation or choking effect in the exhaust if 90 desired.

Another feature of the invention which is herein associated with the foregoing retardation or choking effect is the control of 95 a control valve, whereby the same may be manually rendered operative or inoperative, thereby providing for which is known as the high speed or low speed braking usually required in passenger and freight service respectively. Also associated with this control valve is an electro-pneumatic control whereby when a high speed brake is utilized, said valve will be operated under predetermined conditions to secure a quick 100 brake without any retardation.

105 The full nature of the invention will be understood from the accompanying drawings and the following description and claims.

110 In the drawings, Fig. 1 is a top plan view

of the unitary valve construction, exhaust means associated therewith, a control therefor, and a pipe bracket mounting for said valve. Fig. 2 is an end elevational view of 5 the same. Fig. 3 is a transverse sectional view taken on the line 3—3 of Fig. 4 and in the direction of the arrows with the exhaust removed therefrom, and a portion of the pipe bracket broken away. Fig. 4 is a 10 longitudinal sectional view taken on the line 4—4 of Fig. 3 and in the direction of the arrows. Fig. 5 is a longitudinal sectional view taken on the line 5—5 of Fig. 3 and in the direction of the arrows and illustrates in 15 detail the restricted communication and control therefor. Fig. 6 is a longitudinal sectional view of a portion of the parts shown in Fig. 4 and is similar thereto except that the main valve is shown in a second position. 20 Fig. 7 is a plan view of the valve face and is taken on the line 7—7 of Fig. 6 and in the direction of the arrows. Fig. 8 is a plan view of the valve seat and is taken on the line 8—8 of Fig. 6 and in the direction of 25 the arrows. Fig. 9 is a central sectional view of a graduating adjustable exhaust construction included in the valve construction. Fig. 10 is a transverse sectional view of an electro-pneumatic valve associated 30 with the valve construction. Fig. 11 is a diagrammatic view of the electric and pneumatic connections embodied in the invention. Fig. 12 is an elevational view of the invention taken from the opposite end of 35 that shown in Fig. 2. Fig. 13 is a side elevation of the pipe bracket. Fig. 14 is a front elevational view of the same. Fig. 15 is an enlarged sectional view taken on the line 15—15 of Fig. 5 and in the direction 40 of the arrows.

In Fig. 11 of the drawings there is diagrammatically illustrated the valve construction with its connections and the various controls. In this figure, 20 illustrates 45 a valve body which contains a piston 21. The piston 21 is operated by air pressure upon either face thereof, and said piston in its movement carries a valve member 22 to and fro. The valve member 22 is adapted 50 to sever the connection between the pipe 23 and the pipe 24 (which connection herein includes one portion of the valve body 20) and is adapted to close the pipe 23 and make a connection between the pipe 24 and a discharge pipe or conduit 25. The valve member 22 also is adapted to sever the connection 55 between the lines 26 and 27 connected through and by said valve 22 when in the running position, but disconnected and blanked when in the exhausting or second position. The valve is also adapted to blank and uncover the pipe 24 in the same movement.

The discharge conduit 25 discharges into 60 a chamber 28 which normally communicates

with said conduit 25 by a restricted communication. The conduit also is adapted to communicate with the chamber 28 in free communication by means of a valve 29 carried by a stem 30. Communicating with 70 the chamber 28 is an exhaust construction 31 which may be of any preferred construction, but herein is illustrated as of the graduated type and provided with adjustable means for regulating the same. 75

From the foregoing, therefore, it will be apparent that the exhaust 31 is controlled by the valve 22 and an intermediate control, the valve 29. A piston 32 is carried by the stem 30 and is operable in a chamber 33, one 80 face being exposed to the chamber 28. Pressure is supplied to the chamber 33, to maintain the valve 29 in the closed position, through the conduit 35, which conduit is connected to an electro-pneumatic valve 36. 85 The exhaust construction 31 is shown in detail in Fig. 9 and the electro-pneumatic valve 36 is shown in detail in Fig. 10. The electro-pneumatic valve 36 is provided with an exhaust 37, and pressure is supplied thereto 90 by a conduit 38. The conductors 39 and 40 control said electro-pneumatic valve, and herein the operation of the same is that when current is not supplied to said valve, the pressure supplied through the conduit 38 is 95 cut off, and the air supplied to the cylinder 33 by the conduit 35 formerly in communication with the conduit 38 is exhausted through the port or vent 37, thereby releasing the pressure in the chamber 33 to permit the air pressure in the conduit 25 to open said valve 29 and thus secure free communication to the exhaust 31. The manually operable means 41 is so associated 100 with the valve 29 that said valve may be 105 maintained in an operative condition, or in an inoperative condition, as desired. The purpose of this will be explained hereinafter.

The piston 21 is included in a chamber 42 110 connected by a conduit 43 to another electro-pneumatic valve 44 substantially similar to that shown at 36 and illustrated in detail in Fig. 10. A conduit 45 connects said electro-pneumatic valve 44 with the conduit 38 to 115 a common supply conduit 46. Thus, the electro-pneumatic valves are connected in parallel pneumatically. The electro-pneumatic valve 44 is provided with a vent 47, and said valve construction is adapted to cut off the pressure supplied through the conduit 45 to the chamber 42 through the conduit 43 and exhaust the pressure in said chamber through the vent 47. The operation of this valve is controlled by the circuit wires 48 and 49; the wire 49 and the wire 39 of the other electro-pneumatic valve 36 being connected together to connect said valves in parallel electrically. Suitable 120 means for controlling the circuits 48—49 125 130

and 39—40 may be provided, but herein the same forms no part of the present invention. In Fig. 11 the normal operative positions of the parts are illustrated and the full line 5 arrows indicate the direction of air flow or pressure; while the dotted lines indicate the direction of the air flow after the valves have been operated.

Before proceeding to a description of the 10 valve proper, two of the parts associated therewith and included in the valve construction will be described in detail. In Fig. 11 the numeral 31 indicates an exhaust construction. In Fig. 9 the details of said 15 construction are shown. This valve is known as the "Westinghouse E-7 Speed Valve," and is illustrated in the "Instruction Pamphlet No. 5034—1914," entitled the "L. and N. Passenger Car." The parts of 20 this valve are the body 54, cap nut 55, valve stem 56, stem 57, spring 58, regulating nut 59 and locking ring 60. When the pressure in the cavity 61 is sufficient to overcome the pressure exerted by the tension of the spring 25 58, the valve 56 is raised from its seat, which upward movement closes the end of the port 62 in the valve bushing and opens the ports 63, permitting air to flow through the conduit 61 through the chamber 64 and port 63 30 to the shroud chamber 170 and thence to the atmosphere through the port 171. As the pressure below the valve decreases, the tension of the spring 58 forces the valve 56 downward which restricts the opening at 35 the port 63 to the atmosphere and opens the upper end of the port 62 to the spring chamber 65. Although the spring chamber 65 is open to the atmosphere at all times through the ports 66, these ports are sufficiently small 40 to restrict the exhaust so that the pressure builds up very rapidly in the spring chamber 65 and assists the spring 58 in forcing quickly the valve 56 to its seat. Adjustment of this valve construction is that described 45 in the beforementioned pamphlet and may be observed from Fig. 9. Thus within certain limits the closing pressure can be regulated, as well as the pressure at which the valve will open, and moreover this valve 50 opens and closes with a quick action, permitting air to escape to the atmosphere quickly when opened and causing the valve to seat firmly and promptly when closed. Thus, an adjustable graduating exhaust is 55 secured. The shroud 170 reduces the usual intermittent forceful puff-like exhausts to a pulsating intermittent exhaust. As shown clearly in Fig. 9 and also in Fig. 5, the air discharged through the exhaust construction indicated generally by the numeral 31 passes 60 through a filter or screen 67 from the valve construction, the details of which will be hereinafter described.

Since the electro-pneumatic controls 36 65 and 44, see Fig. 11, are substantially simi-

lar, a description of one will suffice for an understanding of them both, and herein such a construction is illustrated in Fig. 10, and this is substantially a standard construction and is illustrated and described in the 70 "Railway Electrical Engineer," page 313, of September 19, 1919. It may be assumed that we are describing this construction with reference to the electro-pneumatic control 44, and herein the body portion is indicated 75 by said numeral 44. The body portion is connected to the pressure supply pipe 45 and to the outlet or conduit 43. The body 44 is provided with two channels or conduits 87 and 88 which communicate respectively 80 with the conduits 45 and 43. The conduit 87 discharges into a chamber 89 and the conduit 88 communicates with a chamber 90. A plug 91 is provided with a channel 92 and includes a valve seat 93 closed by a 85 conical valve 94 having a stem 95 which extends through the conduit 92. The valve 94 carries a spring seat 96 with which is associated a spring 97 retained in position 90 by a spring retainer and plug closure 98. The spring 97 tends to maintain the valve 96 in closed position. Communicating with the chamber 95 and by means of the plug 91 is a conduit 99 controlled by a valve 100 95 carried by the stem 101. The conduit 99 discharges into the chamber 102, which has free access to the atmosphere at 103. The position of the valve construction hereinbefore described is such that communication is 100 provided between the conduits 45 and 43 105 but when operated it closes or severs said connection and permits the air in the conduit 43 to discharge through the port 103 to the atmosphere. The means for operating 110 said electro-pneumatic valve or control is as follows: A core 101 is threaded into the body portion 44 and has a channel 105 extending longitudinally therethrough. Said channel is adapted to slidably support the valve stem 101. Concentric with the core 104 and supported by the body portion 44 is an electro-magnet 106 which comprises a solenoid having the terminals 107. Said magnet is secured in position and retained 115 therein by the locking nut 108 which engages the core 104. The valve stem 101 which passes through the channel 106 of the core 104 carries an armature 109. Said armature is slidably supported in a cover 120 110, which together with the body portion 111, integral with the body portion 104, forms a closed housing for the one electro-magnet construction. The closure 112 slidably supports an extension 113 of the valve 125 stem 101. When the electro-magnet is energized, the same operates the valve through the armature and maintains communication between the pipes 43 and 45, and said valve operation has been previously described. 130 In order to prevent rotational movement of

the valve by reason of rotational movement of the stem, a pin 114 is interposed in the path of the stem 101; and while permitting longitudinal movement, prevents rotational movement thereof. Deenergization of the electro-magnet permits air in the pipe 43 to exhaust through the port 103.

Reference will now be had more particularly to Figs. 1 to 4 inclusive, and Figs. 12, 13 and 14, wherein the pipe bracket or valve mounting is illustrated. Herein the same is shown including a substantially rectangular plate 50 having the bolt openings 51 at the corners thereof for securing the same to a suitable support, such as the locomotive, and in the most convenient position thereon. Herein said plate 50 is shown provided with a raised portion 68, which raised portion 68 includes a projecting portion 69 provided with a threaded opening 70 by which the valve is secured thereto. Other openings 71 are provided in the raised portion 68 for the same purpose. Herein the raised portion 68 is recessed or channeled at 72, and this channeled construction is adapted, by a suitable gasket means associated therewith, to form leak-proof connections to the valve construction hereinafter to be described. Herein the following openings are provided, 73, 74, 75, 76, 77, 78 and 79.

Each of these openings communicates with a conduit which terminates in a threaded opening. Said threaded openings, as follows, are connected to the before-mentioned openings, respectively, in the recessed portion 72, to-wit: 80, 81, 82, 83, 84, 85 and 86. The threaded opening 80 is adapted to be connected by a conduit 43 to the electro-magnet valve control 44 and supply pressure to and relieve pressure from the chamber 42. The threaded opening 81 is adapted to be connected to the pipe 24. The threaded opening 82 is adapted to be connected to the pipe 23. The threaded opening 83 is adapted to be connected to the pipe 27; and the threaded opening 84 is adapted to be connected to the pipe 26. The threaded opening 85 is adapted to be connected to the conduit 35 supplying pressure to and relieving pressure from the chamber 33 controlled by the other electro-pneumatic valve 36. The threaded opening 86 is adapted to be connected to the fluid pressure line 24^a normally closed by the valve 22.

Reference will now be had particularly to Figs. 3 to 8 inclusive and Figs. 11 and 15 wherein the detailed construction of the automatic valve and associated parts is illustrated in detail. It will be remembered that the valve body has been indicated by the numeral 20, and in said body there is formed a chamber 42. Said chamber 42 is adapted to receive a piston 21 carried by a valve stem 115. The stem 115 extends into and through the chamber 53 within the body 20;

and upon its opposite end there is a piston 116 with which is associated a coiled spring 117 retained in position by a spring closure and cap 118 having a threaded engagement with the closure 119 also having a threaded engagement with the body 20 concentric with the cylinder 53. Mounted within the cylinder or chamber 53 is a tubular sleeve 120 which is recessed at 121 to form a groove or trough adapted to slidably receive the slide or D-valve 22. The slide or D-valve 22 is actuated by the stem 115 which is suitably provided with the enlargements 122 for said purpose. The usual spring 123 is associated with the beforementioned slide and is adapted to maintain said slide valve upon its seat. The valve 22 is provided with a longitudinally extending groove or channel 124 which is offset at 125 and is inclined as at 126. The valve is also provided with a channel or groove 127. The valve seat 121, see Fig. 8, is provided with a port 129; another port 130 in substantial alignment therewith and a port 131 to one side thereof. Also to one side, but oppositely positioned, is a pair of ports 132 and 133. As shown clearly in Figs. 4 and 6, the valve member 22 is adapted to close the port 131 when positioned as shown in Fig. 4, and to maintain the ports 132 and 133 in communication. The valve 22 likewise does not cover the port 129 but does cover the port 130 when in this position. The port 130, however, is adapted to communicate with the chamber 124 by means of the restricted passage 134. This is to permit any air trapped in the passages 124, 125 and 126 to escape therefrom and discharge into the port 130. When the valve member 22 is moved into the position shown in Fig. 4, as hereinafter will be explained more in detail, the communication between port 129 and the chamber 53 is severed, and said port 129 thereupon is connected to the port 130. Likewise, the port 131 is connected to the port 130 while the ports 132 and 133 are disconnected and are blanked.

It will be remembered that the pipe bracket 50 was provided with a recessed channel 72 and three openings 70 and 71. The valve body 20 is provided with a triangular flange 135 by which the same is secured to the pipe bracket 50, as shown most clearly in Figs. 1, 2 and 12 by suitable means such as the bolts 136 and nuts 137 respectively.

Reference will now be had to Figs. 3 and 4, and herein it will be noted that the threaded opening 83 in the pipe bracket through the opening 76 communicates with a registering opening in the valve body which in turn communicates with the passage 138. The threaded opening 84 through the opening 77 similarly communicates with a registering opening in turn communicating with the conduit 139. The conduits 138 and

139 register respectively, see Fig. 8, with the ports 132 and 133 in the valve seat. The threaded opening 85 through the opening 78 and a registering opening in the pipe bracket which communicates with a conduit 140, terminates at 141 in the chamber 33, see Fig. 5. The threaded opening 81 through the port 74 and registering port in the valve body communicates with the conduit 142 that registers with, see Fig. 8, the valve seat opening 129. Likewise, the threaded opening 86 through the opening 79 communicates with a registering opening in the valve body that communicates with a conduit 143 which registers with the opening 131 in said valve seat. The valve seat is also provided with a small opening 144 and the valve body is provided with a small or restricted channel 145. Thus, when the valve 22 is in the normal or running position, that is, with the exhaust construction in non-exhausting position, the air trapped in said exhaust construction escapes through the port 130 and the restricted opening 134 to the channel 124 in the valve, and thence to the valve seat opening 144 and the restricted duct 145 to the atmosphere, to reduce and equalize the same to atmospheric pressure, thereby relieving the pressure in the exhaust construction when the valve 22 is not in the exhausting position. The port 130, see Figs. 3, 4 and 8, communicates with a conduit 146, which conduit 146 is extended laterally at 147 to a body extension 220. The body extension 220 forms a chamber 25, the same as conduit 25 shown in the diagram in Fig. 11. In said body extension 220 there is formed the chamber 28 and the chamber 33. Herein the conduit 25 is formed by a bushing 148 having a valve seat 149 adapted to receive and seat the valve 29. The valve 29 has a stem 150 cross shaped in outline, and this terminates in a projection 151 about which is coiled a compression spring 152 retained in position and under compression by the cap 153. The opposite side of the valve 29 is provided with a boss 154 having a recess 155 adapted to receive the stem 156 of a piston 32. The piston 32 is positioned in the chamber 33 supplied with pressure by the conduit 140 at 141 as previously explained, and the chamber 33 is closed by a head 157, which head is apertured to receive a stem 158 carrying an abutment or bumper 159 positioned within the chamber 133 and adapted to engage the piston 32 for adjusting or limiting the movement thereof. A threaded connection on said stem 158 is shown at 160 and exteriorly positioned and secured to the threaded portion is a hand wheel 161, whereby said bumper may be adjusted laterally with respect to the piston 32 to maintain the piston in any position and thus maintain the valve 29 in closed position or only permit said valve to

be opened to a predetermined amount, depending upon the adjusted stroke of the piston 32. The chamber 28 into which the conduit 25 discharges includes a drain cock 19 and discharges by means of the conduit 162 through the screen 67 to the channel or chamber 61, see Fig. 9, of the exhaust construction previously described, which exhaust construction has a threaded connection 163 as shown in Figs. 5 and 9. 75

Reference will now be had particularly to Figs. 5 and 15, and in these figures the means for securing restricted communication between the chamber 28 and the conduit 25 or conduit 147 is preferably illustrated as included in the valve construction. Broadly, however, it may be independent of said valve construction, although it may be made variable or adjustable by equivalent constructions. Herein the valve 29 is shown provided with a plurality of ports of variable size extending therethrough. Herein the port 164 is shown open; while the port 165 of different diameter is shown closed by a plug 166. Similarly, the ports 167 and 168 are similarly controlled. When it is desired to decrease the amount of restriction in the restricted communication, the desired plug or plugs in the openings or ports 165, 167 and 168 are removed. This provides a readily accessible and removable adjustable construction which could not be obtained if the restricted communication were provided through the body portion. 90

Reference will now be had particularly to Figs. 4, 5, 6 and 11. The operation of the valve construction is as follows: Fluid under pressure is supplied by the pipe 23 to the chamber 53 and this passes through said chamber and through the conduit 24 to the desired destination. The pressure exerted upon the piston 21 to move the same and the valve 22 from the position shown in Fig. 4 to that shown in Fig. 6 is the differential area between the piston 21 and 116 times the pressure supplied to the chamber. Upon the opposite face of the piston 21 and in the chamber 22, there is exerted a pressure substantially equal to the pressure supplied in the pipe 23, but said pressure may be and usually is greater than in the chamber 53. For instance, the pipe 23 may be connected to the feed pipe and train braking system; while the chamber 42 may be connected through the conduits 43, 45 and 46 to the main reservoir and thus be at a slightly increased pressure. The conduit 24 is provided and may be connected to a suitable source of pressure and is connected to the same for relieving the valve or exhausting the same. In the particular system in which this valve has been incorporated, the pipe 24 is connected to the brake pipe or its equivalent. When the electro-pneumatic valve is energized to exhaust through the 110

105

110

115

120

125

130

vent 47, the pressure in the chamber 42 is relieved and said exhaustion permits the pressure in the chamber 53 to move the piston 21 together with the valve 22 into the position in Fig. 6. When in this position, the pipe 24 is cut off from communicating with the chamber 53. If the conduit 23 is directly connected with the conduit 24, then said connection will be severed and the conduit 23 blanked and the conduit 24 connected to the conduit 25 by means of the valve 22. As herein illustrated the conduit 23 is blanked, although it is in free communication with the chamber 53. The pressure in this chamber serves to maintain the slide valve 22 upon its seat and in sealing position. Simultaneously the conduit 24 is connected to said exhaust conduit 25. When the exhausting pressure is supplied to this exhaust conduit, the same passes through the restricted communication into the chamber 28 and thence to the discharge or adjustable graduating exhaust 31. Since, as shown in Fig. 11, high pressure air is supplied to the chamber 33 through the conduit 35 controlled by an electro-pneumatic control 36, the valve 29 will remain seated until such time as said electro-pneumatic control is actuated. When this occurs the pressure in the chamber 33 is relieved but the valve 29 does not open immediately unless the spring 152 is sufficiently strong for such purpose. The valve 29, however, will open immediately upon the supply of air pressure to the conduit 25. When it is desired to prevent or to cut out the operation of the high speed brake and secure only slow speed braking, the hand wheel 161 is turned to force the bumper 159 into engagement with the piston and move said piston to its extreme position for maintaining the valve 29 upon its seat independent of the operation of the electro-pneumatic control 36. In addition to the foregoing arrangement, the operation of the several parts of the valve construction, the conduits 26 and 27 are included as a part of a train braking system and normally are in communication with each other. In certain instances where long trains are handled, what is known as a U-pipe connection is provided as previously explained and the features thereof are retained herein by connecting the pipes 26 and 27 as such through the valve 22. Thus the valve 22 severs said U-pipe connection when moved into the position shown in Fig. 6, and this cooperation among the several parts of the valve is necessary under the before-mentioned conditions, although it may be omitted when said conditions do not apply.

In the foregoing specifications and in the following claims "exhaust" is intended to broadly include any exhaust port or exhaust mechanism unless otherwise modified. Like-

wise, the terminology "pipe, line, conduit, passage" are used interchangeably and are to be considered as equivalents.

While the invention has been described in great detail in the foregoing specifications, the same is to be considered illustrative and not restrictive in character, for the invention consists in the broad combination and assembly of parts whereby a predetermined operation under predetermined conditions and by means of predetermined adjustments can be obtained. The various modifications which will readily suggest themselves to those skilled in the art to which this invention applies are all considered to be within the broad purview of the invention as outlined by the appended claims.

The invention claimed is:

1. A valve construction including in combination a pipe, an exhaust therefor, a conduit normally connecting said pipe and said exhaust in restricted communication, and valve means for connecting said pipe and said exhaust in free communication.

2. A valve construction including in combination a pipe, a graduating exhaust therefor, a conduit normally connecting said pipe and said exhaust in restricted communication, and valve means for connecting said pipe and said exhaust in free communication.

3. A valve construction including in combination a pressure supplying pipe, an exhaust therefor, a conduit normally connecting said pipe and said exhaust in restricted communication, and valve means operable by the exhausting pressure supplied thereto by the pressure supplying pipe for connecting the same to the exhaust in free communication.

4. A valve construction including in combination a pipe, an exhaust therefor, a conduit normally connecting said pipe and said exhaust in restricted communication, valve means for connecting said pipe and said exhaust in free communication, and manually operable means for preventing valve operation.

5. A valve construction including in combination a pipe, an exhaust therefor, a conduit normally connecting said pipe and said exhaust in restricted communication, valve means for connecting said pipe and said exhaust in free communication, and pneumatic means for controlling said valve.

6. A valve construction including in combination a pipe, an exhaust therefor, a conduit normally connecting said pipe and said exhaust in restricted communication, valve means for connecting said pipe and said exhaust in free communication, and electric means for controlling said valve.

7. A valve construction including in combination a pipe, an exhaust therefor, a conduit normally connecting said pipe and said

- exhaust in restricted communication, valve means for connecting said pipe and said exhaust in free communication, and electro-pneumatic means controlling said valve.
- 5 8. A valve construction including in combination a pipe, an exhaust therefor, a conduit normally connecting said pipe and said exhaust in restricted communication, valve means for connecting said pipe and said exhaust in free communication, pneumatic means for controlling said valve, and manually operable means for preventing valve operation.
- 15 9. A valve construction including in combination a pipe, an exhaust therefor, a conduit normally connecting said pipe and said exhaust in restricted communication, valve means for connecting said pipe and said exhaust in free communication, electric means for controlling said valve, and manually operable means for preventing valve operation.
- 25 10. A valve construction including in combination a pipe, an exhaust therefor, a conduit normally connecting said pipe and said exhaust in restricted communication, valve means for connecting said pipe and said exhaust in free communication, electro-pneumatic means controlling said valve, and manually operable means for preventing valve operation.
- 35 11. A valve construction including in combination a pipe, an exhaust therefor, a conduit normally connecting said pipe and said exhaust in restricted communication, valve means for connecting said pipe and said exhaust in free communication, and an unbalanced pneumatic control for said valve operable when the unbalancing is reversed.
- 40 12. A valve construction including in combination a pipe, an exhaust therefor, a conduit normally connecting said pipe and said exhaust in restricted communication, valve means for connecting said pipe and said exhaust in free communication, an unbalanced pneumatic control for said valve operable when the unbalancing is reversed, and electrical means for reversing the unbalancing.
- 45 13. A valve construction including in combination a pipe, an exhaust therefor, a conduit normally connecting said pipe and said exhaust in restricted communication, valve means for connecting said pipe and said exhaust in free communication, an unbalanced pneumatic control for said valve operable when the unbalancing is reversed, and manually operable means for preventing valve operation independent of the exhausting pneumatic condition.
- 55 14. A valve construction including in combination a pipe, an exhaust therefor, a conduit normally connecting said pipe and said exhaust in restricted communication, valve means for connecting said pipe and said exhaust in free communication, an unbalanced
- pneumatic control for said valve operable when the unbalancing is reversed, electrical means for reversing the unbalancing, and manually operable means for preventing valve operation independent of the exhausting pneumatic condition.
- 60 15. A valve construction including in combination a pipe, an adjustable exhaust therefor, a conduit normally connecting said pipe and said exhaust in restricted communication, and valve means for connecting said pipe and said exhaust in free communication.
- 65 16. A valve construction including in combination a pipe, an adjustable graduating exhaust therefor, a conduit normally connecting said pipe and said exhaust in restricted communication, and valve means for connecting said pipe and said exhaust in free communication.
- 75 17. A valve construction including in combination a pressure supplying pipe, an adjustable exhaust therefor, a conduit normally connecting said pipe and said exhaust in restricted communication, and valve means operable by the exhausting pressure supplied thereto by the pressure supply pipe for connecting the same to the exhaust in free communication.
- 80 18. A valve construction including in combination a pressure supplying pipe, a graduating exhaust therefor, a conduit normally connecting said pipe and said exhaust in restricted communication, and valve means operable by the exhausting pressure supplied thereto by the pressure supply pipe for connecting the same to the exhaust in free communication.
- 85 19. A valve construction including in combination a pressure supplying pipe, an adjustable graduating exhaust therefor, a conduit normally connecting said pipe and said exhaust in restricted communication, and valve means operable by the exhausting pressure supplied thereto by the pressure supply pipe for connecting the same to the exhaust in free communication.
- 90 20. A valve construction including in combination a pipe, an adjustable exhaust therefor, a conduit normally connecting said pipe and said exhaust in restricted communication, valve means for connecting said pipe and said exhaust in free communication, and manually operable means for preventing valve operation.
- 95 21. A valve construction including in combination a pipe, an adjustable graduating exhaust therefor, a conduit normally connecting said pipe and said exhaust in restricted communication, valve means for connecting said pipe and said exhaust in free communication, and manually operable means for preventing valve operation.
- 100 22. A valve construction including in combination a pressure supplying pipe, an ad-

- justable exhaust therefor, a conduit normally connecting said pipe and said exhaust in restricted communication, valve means operable by the exhausting pressure supplied thereto by the pressure supply pipe for connecting the same to the exhaust in free communication, and manually operable means for preventing valve operation. 5
23. A valve construction including in combination a pressure supplying pipe, a graduating exhaust therefor, a conduit normally connecting said pipe and said exhaust in restricted communication, valve means operable by the exhausting pressure supplied thereto by the pressure supply pipe for connecting the same to the exhaust in free communication, and manually operable means for preventing valve operation. 10
24. A valve construction including in combination a pressure supplying pipe, an adjustable graduating exhaust therefor, a conduit normally connecting said pipe and said exhaust in restricted communication, valve means operable by the exhausting pressure supplied thereto by the pressure supply pipe for connecting the same to the exhaust in free communication, and manually operable means for preventing valve operation. 15
25. A valve construction including in combination a pipe, an exhaust therefor, a conduit normally connecting said pipe and said exhaust in restricted communication, means for varying the restriction in said communication, and valve means for connecting said pipe and said exhaust in free communication. 20
26. A valve construction including in combination a pipe, a graduating exhaust therefor, a conduit normally connecting said pipe and said exhaust in restricted communication, means for varying the restriction in said communication, and valve means for connecting said pipe and said exhaust in free communication. 25
27. A valve construction including in combination a pipe, an adjustable exhaust therefor, a conduit normally connecting said pipe and said exhaust in restricted communication, means for varying the restriction in said communication, and valve means for connecting said pipe and said exhaust in free communication. 30
28. A valve construction including in combination a pipe, an adjustable graduating exhaust therefor, a conduit normally connecting said pipe and said exhaust in restricted communication, means for varying the restriction in said communication, and valve means for connecting said pipe and said exhaust in free communication. 35
29. A valve construction including in combination a pipe, an exhaust therefor, a conduit normally connecting said pipe and said exhaust in restricted communication, means for varying the restriction in said communication, and valve means for connecting said pipe and said exhaust in free communication. 40
30. A valve construction including in combination a pipe, an adjustable exhaust therefor, a conduit normally connecting said pipe and said exhaust in restricted communication, means for varying the restriction in said communication, valve means for connecting said pipe and said exhaust in free communication, and manually operable means for preventing valve operation. 45
31. A valve construction including in combination a pipe, an adjustable exhaust therefor, a conduit normally connecting said pipe and said exhaust in restricted communication, means for varying the restriction in said communication, valve means for connecting said pipe and said exhaust in free communication, and manually operable means for preventing valve operation. 50
32. The combination of an exhaust, a plurality of normally open fluid pressure lines, another and normally closed fluid pressure line, and a single valve means for closing said normally open fluid pressure lines and for connecting one of said closed lines and the normally closed line to said exhaust. 55
33. The combination of an exhaust, a plurality of normally open fluid pressure lines, another and normally closed fluid pressure line, a single valve means for closing said normally open fluid pressure lines and for connecting one of said closed lines and the normally closed line to said exhaust, and a balanced pneumatic control for controlling said valve. 60
34. The combination of an exhaust, a plurality of normally open fluid pressure lines, another and normally closed fluid pressure line, a single valve means for closing said normally open fluid pressure lines and for connecting one of said closed lines and the normally closed line to said exhaust, a balanced pneumatic control for controlling said valve, and an electrical control for distributing said balance. 65
35. The combination of an exhaust conduit, an exhaust therefor, a restricted communication between said exhaust and said exhaust conduit, a plurality of normally open fluid pressure lines, another and normally closed fluid pressure lines, a single valve means for closing said normally open fluid pressure lines and for connecting one of said closed lines and the normally closed line to said exhaust conduit, and means controlling the restricted communication between said exhaust conduit and said exhaust. 70
36. The combination of an exhaust conduit, an exhaust therefor, a restricted communication between said exhaust and said exhaust conduit, a plurality of normally open fluid pressure lines, another and nor- 75

- 5 mally closed fluid pressure lines, a single valve means for closing said normally open fluid pressure lines and for connecting one of said closed lines and the normally closed line to said exhaust conduit, and electrically operable means controlling the restricted communication between said exhaust conduit and said exhaust. 70
- 10 37. The combination of an exhaust conduit, an exhaust therefor, a restricted communication between said exhaust and said exhaust conduit, a plurality of normally open fluid pressure lines, another and normally closed fluid pressure lines, a single valve means for closing said normally open fluid pressure lines and for connecting one of said closed lines and the normally closed line to said exhaust conduit, and pneumatically operable means controlling the restricted communication between said exhaust conduit and said exhaust. 75
- 15 38. The combination of an exhaust conduit, an exhaust therefor, a restricted communication between said exhaust and said exhaust conduit, a plurality of normally open fluid pressure lines, another and normally closed fluid pressure line, a single valve means for closing said normally open fluid pressure lines and for connecting one of said closed lines and the normally closed line to said exhaust conduit, and electro-pneumatically operated means controlling the restricted communication between said exhaust conduit and said exhaust. 80
- 20 39. The combination of an exhaust conduit, an exhaust therefor, a restricted communication between said exhaust and said exhaust conduit, a plurality of normally open fluid pressure lines, another and normally closed fluid pressure line, a single valve means for closing said normally open fluid pressure lines and for connecting one of said closed lines and the normally closed line to said exhaust conduit, and means operable by the exhausted pressure controlling the restricted communication between said exhaust conduit and said exhaust. 85
- 25 40. The combination of an exhaust conduit, an exhaust therefor, a restricted communication between said exhaust and said exhaust conduit, a plurality of normally open fluid pressure lines, another and normally closed fluid pressure line, a single valve means for closing said normally open fluid pressure lines and for connecting one of said closed lines and the normally closed line to said exhaust conduit, and manually operable means for preventing the operation of said controlling means. 90
- 30 41. The combination of an exhaust conduit, an exhaust therefor, a restricted communication between said exhaust and said exhaust conduit, a plurality of normally open fluid pressure lines, another and normally closed fluid pressure line, a single valve means for closing said normally open fluid pressure lines and for connecting one of said closed lines and the normally closed line to said exhaust conduit, and a plurality of normally closed fluid pressure lines, another and normally open fluid pressure lines, a single valve means for closing said normally open fluid pressure lines and for connecting one of said closed lines and the normally closed line to said exhaust conduit, means operable by the exhausted pressure controlling the restricted communication between said exhaust conduit and said exhaust, and manually operable means for preventing the operation of said controlling means. 95
- 35 42. The combination of a fluid pressure conduit, an exhaust conduit therefor, a valve controlling said exhaust conduit, an exhaust, a restricted communication between said exhaust conduit and said exhaust, and a second valve for securing unrestricted communication therebetween. 100
- 40 43. The combination of a pair of normally communicating fluid pressure lines, a third fluid pressure line, an exhaust conduit, a valve for severing the communication between said pair of lines and connecting one of said connected lines and said third line to the exhaust conduit, an exhaust, a restricted communication between said exhaust conduit and said exhaust, and a second valve for securing unrestricted communication therebetween. 105
- 45 44. The combination of a fluid pressure conduit, an exhaust conduit therefor, a valve controlling said exhaust, an exhaust, a restricted communication between said exhaust conduit and said exhaust, a second valve for securing unrestricted communication therebetween, and means for varying the restriction in said communication. 110
- 50 45. The combination of a pair of normally communicating fluid pressure lines, a third fluid pressure line, an exhaust conduit, a valve for severing the communication between said pair of lines and connecting one of said connected lines and said third line to the exhaust conduit, an exhaust, a restricted communication between said exhaust conduit and said exhaust, a second valve for securing unrestricted communication therebetween, and means for varying the restriction in said communication. 115
- 55 46. The combination of a fluid pressure conduit, an exhaust conduit therefor, a valve controlling said exhaust conduit, an exhaust, a restricted communication between said exhaust conduit and said exhaust, a second valve for securing unrestricted communication therebetween, and manually operable means preventing the operation of said second valve. 120
- 60 47. The combination of a pair of normally communicating fluid pressure lines, a third fluid pressure line, an exhaust conduit, a valve for severing the communication between said pair of lines and connecting one of said connected lines and said third line to the exhaust conduit, an exhaust, a re- 125
- 65 130

stricted communication between said exhaust conduit and said exhaust, a second valve for securing unrestricted communication therebetween, and manually operable means for preventing the operation of said second mentioned valve.

48. The combination of a pair of normally communicating fluid pressure lines, a third fluid pressure line, an exhaust conduit, 10 a valve for severing the communication between said pair of lines and connecting one of said connected lines and said third line to the exhaust conduit, an exhaust, a restricted communication between said exhaust conduit 15 and said exhaust, a second valve for securing unrestricted communication therebetween, means for varying the restriction in said communication, and manually operable means for preventing the operation of said 20 second mentioned valve.

49. The combination of a fluid pressure conduit, an exhaust conduit therefor, a valve

controlling said exhaust conduit, an exhaust, a restricted communication between said exhaust conduit and said exhaust, a second 25 valve for securing unrestricted communication therebetween, means for varying the restriction in said communication, and manually operable means for preventing the operation of said second valve.

50. A valve construction including in combination a pipe, an adjustable graduating exhaust therefor, a conduit normally connecting said pipe and said exhaust in restricted communication, means for varying the restriction in said communication, valve means for connecting said pipe and said exhaust in free communication, and manually operable means for preventing valve operation.

In witness whereof, I have hereunto affixed my signature.

CLINTON F. SHADLE.
